LAND ANCHOR

Rowland Rushworth Hirst and Arnold Hirst,
Halifax, EnglandApplication December 4, 1929, Serial No. 411,608,
and in Great Britain December 4, 1928

2 Claims. (Cl. 189—90)

The invention relates to an anchorage, for the height-adjusting means of tennis nets comprising a socket having a vertical bore and containing two spaced pistons with means to connect the net adjusting means to the upper side of the upper piston, a removable projection extending inwardly from the wall of the socket into the space between the pistons so as to limit their sliding movement within the socket. In an equivalent construction, a block slideable in the bore of the socket is substituted for the two spaced pistons, such block having a longitudinal recess in its surface to receive the projection from the wall of the socket, means for attaching the net adjusting means being provided at the upper end of the block.

It is necessary that the connection between the net adjusting means and the sliding pistons or block shall be of a readily detachable nature, so as to permit of removal of the net when so desired, and it has been usual to employ a form of connection in which a shank extending upwardly from the pistons or block was bent into an open hook with which an eye on the height adjusting means could be engaged.

It has been found in practice that there is, occasionally, a tendency for the height adjusting means to become accidentally detached from the anchorage if, for instance, a ball should strike in a certain direction either the height adjusting means or the net adjacent such means, and the present invention has for its object to provide a form of connection between the height adjusting means and the anchorage which, whilst permitting of the connection being readily made or unmade, cannot become detached accidentally.

In carrying out the invention, we form or provide on the upper surface of the upper piston or on the upper end of the block, two vertical spaced lugs and between these lugs we mount pivotally the boss of a hook member. The free end of this hook member is adapted to abut against or cooperate with a projection extending vertically upwards from the piston or block, so as to close the entrance to the hook and form as it were an eye, whilst on the rear side of the hook member there is a projection adapted to be engaged by a spring plunger carried by the pistons or block, the arrangement being such that the free end of the hook is normally held in contact with its stop or cooperating fixed part.

Referring to the accompanying drawing,

Fig. 1 shows a device having our present improvement applied, and

Fig. 2 is a detail showing the hook member in

open position for the insertion of the eye of the height adjusting means.

In the drawing *a* represents the socket having the vertical bore *a'*, and *b*, *b*, the two spaced pistons into the space between which projects a set 60 screw *c* extending through a threaded opening in the wall of the socket and serving to limit the vertical sliding movement, within the bore of the socket, of the block constituted by the two pistons and their connecting member. 65

According to the present improvement, we provide on the upper surface of the upper piston or block, two vertical lugs such as *d*, suitably spaced apart and between these lugs we pivot the boss of a hook member *e*. Extending upwardly from the upper piston is a projection *f* with the upper end of which the free end of the hook member *e* is adapted to cooperate, as shown in Fig. 1, to close the entrance to the hook and with the hook form a retaining eye. On the rear 75 side of the hook member is a projection *e'* adapted to be engaged by a spring plunger *g* carried by the pistons or block and arranged normally to hold the free end of the hook in contact with the part *f*. 80

To insert the eye *h'* of the height adjusting means *h*, the hook member *e* is rocked backwardly as shown in Fig. 2 against the pressure of the spring plunger so as to provide a gap *i* between the free end of the hook member and the fixed 85 projection *f*. The eye having been inserted, the hook member is released, and thereupon the spring plunger acts to move the hook member back to closed position, and to maintain it in that position. 90

The location of the spring plunger *g* behind the hook member facilitates the application of the height adjusting means, since to open the hook it is necessary to apply pressure in such a manner that the natural tendency for the pistons 95 or block to slide downwardly in the socket is resisted.

Having thus described our invention, what we claim as new and desire to secure by Letters Patent is:—

1. A device of the character described comprising a socket, a member slideable in said socket comprising a pair of vertically spaced and connected piston elements, a hook pivotally mounted on the upper face of the uppermost piston, an 105 upstanding projection formed with the upper face of said uppermost piston for engagement with the free end of said hook to close the same, said hook being formed with a lateral projection on the back thereof, a plunger extending verti- 110

cally through said pistons and slidably mounted therein and having its upper end engaging said last mentioned projection, and a spring carried on said plunger between said pistons and engaging one of said pistons to normally urge said plunger against said projection on the back of said hook to urge the free end of the hook into engagement with said upstanding projection.

2. A device of the character described comprising a socket, a member slidable in said socket comprising a pair of vertically spaced and connected piston elements, a hook pivotally mounted on the upper face of the uppermost piston, an upstanding projection formed with the upper face

of said uppermost piston for engagement with the free end of said hook to close the same, said hook being formed with a lateral projection on the back thereof, a plunger extending vertically through said pistons and slidably mounted therein and having its upper end engaging said last mentioned projection, and yielding means associated with said plunger and engaging one of said pistons to normally urge said plunger against said projection on the back of said hook to urge the free end of the hook into engagement with said upstanding projection.
